US0D1105359S

(12) **United States Design Patent** (10) **Patent No.:** **US D1,105,359 S**
(45) **Date of Patent:** **** Dec. 9, 2025**

(54) **DISPENSER**

- (71) Applicant: **Bradley Fixtures Corporation**, Menomonee Falls, WI (US)
- (72) Inventors: **Darnell Wesson**, Menomonee Falls, WI (US); **Will Haas**, Menomonee Falls, WI (US); **Mark Meyer**, Menomonee Falls, WI (US); **Laura Stang**, Menomonee Falls, WI (US); **James A. Wollmer**, Menomonee Falls, WI (US); **Douglas Carpiaux**, Milwaukee, WI (US); **Emily Schoenfelder**, Milwaukee, WI (US)
- (73) Assignee: **Bradley Fixtures, LLC**, Menomonee Falls, WI (US)
- (**) Term: **15 Years**
- (21) Appl. No.: **29/850,174**
- (22) Filed: **Aug. 17, 2022**

Related U.S. Application Data

CLAIM

The ornamental design for a dispenser as shown and described.

DESCRIPTION

FIG. 1 is a front, right, perspective view of the claimed design;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The ornamental design which is claimed is shown in solid lines in the drawings. The evenly dashed broken lines illustrate portions of the dispenser that form no part of the claimed design.

1 Claim, 6 Drawing Sheets

Related U.S. Application Data

division of application No. 29/645,489, filed on Apr. 26, 2018, now Pat. No. Des. 886,245.
